PRESSURE BLOOD INFUSER

Joseph E. Mason, Melville, N.Y., assignor to New Dimensions Research Corporation, Old Bethpage, N.Y.

Filed May 25, 1973, Ser. No. 363,862

Term of patent 14 years

Int. Cl. D24—02

U.S. Cl. D83—1 F

FIG. 1 is a perspective view of a pressure blood infuser showing my new design with the pressure plate in a partially retracted active position;

FIG. 2 is a perspective view opposite that of FIG. 1 with the pressure plate in its inactive position;

FIG. 3 is a bottom plan view; and

FIG. 4 is a side view.

I claim:

The ornamental design for a pressure blood infuser, substantially as shown and described.
